FOOT SUPPORT

Walter Wisbrun, Dusseldorf, Germany

Application September 20, 1933, Serial No. 690,247
In Germany July 31, 1933

5 Claims. (Cl. 36—71)

The object of the invention is a foot support consisting of a convex foot plate for the arch of the foot. Previous foot supports of this character had the disadvantage that they were not suitable for relieving the pain of the so-called "front-foot" or "splay-foot". This has been due to the front end or the front edge of the foot plate not having been adapted to the formation of the metatarsal bones, insufficient attention having been given to their shape and position with respect to each other.

The erroneous assumption has been started from a concept that the cross-section through the metatarsal bone caps corresponded to a transverse arch and it has consequently been attempted to support this transverse arch by hump-like elevations on the front end of the foot plate or insertion.

Experience has, however, shown that it is exactly the shape and position of the five metatarsal bones, which, behind their joint caps, form downwardly concave arcs and together form an almost straight and forwardly directed bulge, that must be taken into consideration in the construction of the foot plate at its front edge.

This point of view is taken into account by the improved foot support which thereby reliably relieves pain due to "front-foot" or "splay-foot" or prevents its occurrence. It is characterized by the convexly arched foot plate, which affords a carrying support to the foot at its frontally directed apex line located under the front end of the heel bone, having at its front edge a strip running almost straight and bent downwards, which forms with the frontal axis an angle of 15°—20°. By this combination of the support under the front end of the heel bone by the foot plate with the support by the turned-over strip at the front edge of the foot plate which corresponds to the bulging out of the metatarsal bones behind the joint caps, the result is attained that the foot obtains in a novel manner a support corresponding to the shape of its longitudinal arch, which has hitherto not been the case. A drooping and twisting over of the bones of the foot, as also a dropping of the front of the foot, is hereby simultaneously corrected or avoided.

In this supporting of the longitudinal arch, however, lies the superiority of the improved foot support as compared with previous ones.

An embodiment of the improved foot support is shown as an example in the accompanying drawing.

Fig. 1 shows the foot support on a foot, in elevation.

Fig. 2 is a bottom view corresponding to Fig. 1.

Fig. 3 is a vertical section on the line A—B of Fig. 1.

The foot support consists of the convex foot plate 1 adapted to the arch of the foot, and the highest point of which is located as a frontally directed apex line 2 under the front end of the heel bone 3. The front part of this foot plate carries a frontal, strip-like, bent-over part 4 corresponding to the bent-out shape of the metatarsal bones 5 behind their joint caps 6. The angle which this turned-over strip 4 forms with the frontal axis amounts to about 15°—20°. In this way, the result is attained that the foot is supported in the direction of its longitudinal arch by the apex line 2 at the end of the heel bone 3 and behind the joint caps 6 of the metatarsal bones 5 by the turned strip 4.

This form of construction is adapted both to the making of individual insertions after stamp impressions or plaster casts as also for fitting into orthopædic boots. In order with these latter to ensure an individual support, provisions are made on the supports fitted into the boot which permit the attachment of elevations of all kinds. Such elevations may be: an elevation under the front end of the heel bone, an inner elevation and an outer elevation according to whether the foot is inclined to tread the boot at an inclination towards the inside or towards the outside, and, finally, an elevation on the front part, in particular the turned-down edge strip.

Having now particularly described and ascertained the nature of my said invention and in what manner the same is to be performed, I declare that what I claim is:—

1. A foot support consisting of a stiff plate having a substantially flat central portion, a rear portion extending at a slight angle downwardly from the rear end of the central portion and terminating in a rear edge portion extending downwardly at an angle from the rear edge of the rear portion, and a front portion extending downwardly at an angle to the central portion from the front edge of said central portion.

2. A foot support consisting of a stiff plate having a substantially flat central portion, a rear portion extending at a slight angle downwardly from the rear end of the central portion and terminating in a rear edge portion extending downwardly at an angle from the rear edge of the rear portion, and a front portion extending downwardly at an angle to the central portion from the front edge of said central portion, said front

portion and the front edge of the central portion being positioned at 15° to 20° inclination to a line parallel to a transverse axis of the plate.

3. A foot support consisting of a stiff plate having a substantially straight central portion, a portion adjoining the straight portion at the rear extending downwardly at an obtuse angle to the central portion, the last mentioned portion having an extremity extending downwardly therefrom at an angle more acute than the angle between the straight portion and the said adjoining portion thereof, and a support for the front end of the plate.

4. A foot support consisting of a stiff plate having a substantially straight central portion, a portion adjoining the straight portion at the rear extending downwardly at an obtuse angle to the central portion, the last mentioned portion hav-

ing an extremity extending downwardly therefrom at an angle more acute than the angle between the straight portion and the said adjoining portion thereof, and a portion at the front of the central portion extending diagonally downwardly and longitudinally of the central portion.

5. A foot support consisting of a stiff plate having a substantially flat central portion and a portion adjoining the rear of the central portion, the second mentioned portion extending downwardly at an obtuse angle for a portion of its length and terminating in an extremity extending downwardly at an acute angle as compared with the angle of divergence of the second mentioned portion with respect to the central portion of the plate, and a support for the front end of the plate.

WALTER WISBRUN.
